DESIGN FOR A PLATFORM WEIGHING SCALE

Leverett D. Chambers, New York, N. Y., assignor
to Peerless Weighing Machine Company, New
York, N. Y., a corporation of Maine

Application November 12, 1932, Serial No. 45,942

Term of patent 14 years

To all whom it may concern:

Be it known that I, LEVERETT D. CHAMBERS, residing at New York city, county and State of New York, a citizen of the United States, have invented a new, original, and ornamental Design for a Platform Weighing Scale, of which the following is a specification, reference being had to the accompanying drawing, forming part hereof.

In the drawing:

Figure 1 is a perspective view of the scale showing my new design; and

Fig. 2 is a front elevation thereof.

In the drawing the vertical shading and the horizontal shading, respectively, indicate different colors.

I claim:

The ornamental design for a platform weighing scale, as shown and described.

LEVERETT D. CHAMBERS.
